UNITED STATES PATENT OFFICE.

PERCY HERBERT STEVENS, OF NORTHAMPTON, ENGLAND, ASSIGNOR TO SMITH, MAJOR & STEVENS LIMITED, OF ABBEY WORKS, NORTHAMPTON, ENGLAND.

CONTROL OF POLYPHASE ELECTROMOTORS.

Application filed August 3, 1925, Serial No. 47,887, and in Great Britain August 15, 1924.

This invention relates to means for controlling the speed of polyphase electro-motors, and is especially adapted for use where polyphase motors having commutator 5 brushes are employed for operating lifts and in which it is desirable to control the speed of the motor from the lift cage, so as to increase the speed after the cage has started and to restore the speed to normal; as the 10 floor where the stopping is to take place, is approached.

Polyphase motors of the type referred to have already been fitted with means for adjusting their speed. One such arrangement 15 consists of means for rocking the commutator brushes and thus increasing the speed of the motor, and by rocking the brushes back to their normal position the normal speed may again be resumed.

20 In some cases the brushes are arranged in two sets relatively to one another so as to rock in opposite directions simultaneously, the said brushes being in such a construction carried on rocker rings concentric to the 25 motor shaft and being moved equally in opposite directions by means of spur gearing. The rotation of such gearing in one direction gives both rocker rings angular movement from the normal position, one in a clockwise 30 direction and the other in a counter-clockwise direction, and the reversing of the spur gearing allows the two sets of brushes to be returned to the normal position where the normal speed of the motor is resumed.

35 Hitherto the rocking of the rocker rings for speed adjustment has been achieved either by hand or by means of an independent pilot motor.

Now the object of the present invention is 40 to construct means for adjusting commutator brushes by the mere operation of clutch mechanism which, on being brought into action, enables movement to be transmitted from a moving part of the lift mechanism 45 to the control mechanism for adjusting the position of the brushes. The clutch referred to is operated from the lift cage to open and close electrically, in such a manner that on the clutch being operated, some moving 50 part of the lift, such for instance as the drum shaft, is caused to operate the change mechanism and to move such part or parts of the polyphase motor as to cause the brushes to be moved in their proper relationship and 55 thus increase the speed of the motor; whilst

on the clutch being disconnected also from the lift cage or other control point remote from the motor, the gear becomes free to return, and the brushes are carried back to their normal position either by weight or 60 spring action.

The speed of travel of the lift is thus 65 under complete control of the operator in the cage, and he is able to start the lift in the ordinary way, and without operating the control mechanism the lift may travel slowly to its destination and the current may be cut off from the motor in the present way; or after the lift has been started under normal conditions, it may then be accelerated 70 by the operator introducing the clutch mechanism which effects the adjustment of the brushes, and the increased speed is added smoothly by the operation of the lift winding gear. The maximum speed may be continued until the operator cuts out the clutch and thus returns the motor to its normal speed immediately prior to finally cutting off the current from the motor in order to stop accurately and smoothly at the pre-determined floor level.

75 In the accompanying drawings, examples of construction of mechanism according to this invention are illustrated, Figure 1 being a plan view of a clutch mechanism and 80 means for moving the brush rocker rings. Figure 2 is an elevation of the clutch mechanism, and Figure 3 an elevation showing means for moving the rocker rings. Figures 85 4 and 5 are front and side elevations showing a modification of the means for moving the rocker rings, and Figure 6 shows a further modification. Fig. 7 diagrammatically illustrates the driving motor, brush shifting 90 means, the clutch, the connection between the clutch and the lift and the electric circuit for the clutch.

95 Referring particularly to Figures 1, 2 and 3 of the drawings, a shaft A carries a spur 100 wheel B which engages with a rack formed on one of the brush rocker rings C, and the other brush rocker ring C¹ which requires to be adjusted in the opposite direction, gears with an intermediate spur wheel C⁶ and thence to a spur wheel B¹ on the shaft 105 A. This shaft also carries a drum D to which three chains are connected. One of these chains E carries a weight E¹ which tends to move and to retain the shaft A in the position where, through the spur gearing, 110

the rocker rings hold the brushes for the motor when running at the lowest speed. The other two chains F, F¹ pass over the top of the chain drum and extend to the 5 clutch drum G, one of the chains F being attached to the upper side of the clutch drum, and the second chain F¹ to the under side of the said drum. Thus, by the clutch drum rotating clockwise or anti-clockwise, 10 one or other of the chains is pulled, and the chain drum on the first-mentioned shaft is rotated in one direction regardless of the direction of rotation of the clutch drum.

The clutch drum G is carried on some 15 moving part of the lift mechanism, and preferably on the lift shaft, so that on the clutch being actuated either during the ascent or descent of the lift, one or other of the chains F, F¹ is pulled and the brush 20 rocker rings C moved with their brushes, and thus the speed of the motor is accelerated.

The clutch operating the clutch drum G is operated magnetically by a current received from the lift cage. All the time this 25 auxiliary or shunt current is passing, the clutch is operated sufficiently to continue to move the rocker rings C in opposite directions, so as to adjust the brushes until the 30 maximum speed is reached, when the clutch may be permitted to slip and yet retain, through the chain connection F, F¹ and gear, the brushes in position to maintain the motor at the maximum speed. When the operator 35 cuts off the auxiliary current, the clutch drum G is free to rotate, and the weight E¹ carried by the chain drum D rotates the shaft A carrying the spur gearing B and returns the brush rocker rings C to their 40 normal position, and the speed of the motor is reduced to its normal rate.

Referring particularly to Figures 4 and 5, which show both rocker rings C and C¹ carrying commutator brushes C² bearing 45 upon the commutator C⁷ of the motor, the brush rocker rings are carried in a frame C⁸ which is provided with anti-friction rollers C⁹ entering grooves in the peripheries of the rocker rings. Brackets C¹⁰ are attached 50 to the rocker rings and extend outside the frame C⁸ and carry outwardly extending arms C³, C⁴. To the arms C³ are attached weights E¹, and the arms C⁴ are connected by chains or rods H to levers J rigidly 55 mounted on a shaft K which is mounted in bearings in the main frame of the motor.

Chains F and F¹ attached to the upper and under side of the drum D are connected at their opposite ends with a lever L also 60 fast on the shaft K. Upon the clutch being actuated, the drum D will be revolved, and through one or other of the chains F, F¹, according to which direction the drum D is 65 rotated, the lever L will be pulled and rock the shaft K, and through levers J and chains

or rods H the rocker rings C, C¹ will be moved in opposite directions, and will continue to move until lugs C⁵ formed on the rocker rings C, C¹ contact with stops provided at suitable positions on the main frame 70 of the motor, when the maximum speed is reached and the clutch is permitted to slip and yet retain the lugs C⁵ in contact with the stop M. Upon the disengagement of the 75 clutch mechanism, the weights E¹ will move the rocker rings back to their original position, and the lugs C⁶ will contact with the stops M.

Figure 6 shows an arrangement of mechanism, whereby one weight E¹ will return 80 both the rocker rings to their original position after they have been revolved. As shown in this figure, the levers J mounted on the shaft K are connected to the rocker rings C, C¹ by rods H, and a lever N also 85 fixed to the shaft K carries the weight E¹, and the speed at which the weight returns the rocker rings from the high speed to the low speed position is controlled by means of a dash-pot O. A dash-pot could of course 90 be applied to control the speed of the return movement of the brushes in any arrangements to which the invention is applied.

Referring to the diagram Fig. 7, a control lever P, which is conveniently mounted 95 on the lift cage, may be rocked to right or left according to the direction, up or down, required for the lift. When the lever P is rocked to the position shown in dotted lines, 100 the lift starts in an upward direction and travels at its minimum speed. Upon the operator rocking the control lever P further to the left, a shunt or auxiliary current passes to the solenoid Q which moves 105 the solenoid core, thus operating the clutch and causing the drum G to be gripped to the shaft G¹ which is driven from the lift shaft R, pulling the chains F or F¹, rocking the lever J and pulling down the rods H, 110 thus rocking the brush rocker rings C, C¹, through the medium of the arms C⁴ and brackets C¹⁰ and progressively increasing the speed of the lift.

The operator, before reaching his destination, brings the lever P again to the dotted line position whereby the clutch drum G is freed from the shaft G¹ and the brush rocker rings C, C¹ are returned to their normal positions by the weights E¹, E¹. 120 The lift thus slows down to its minimum speed prior to the current being cut off from the motor by bringing the lever P to its final central position when the lift arrives.

What I claim as my invention and desire 125 to secure by Letters Patent is:—

1. In association with a lift having a rotary part and operated by a polyphase motor having a commutator and commutator brushes the combination of a clutch having 130

a driving and a driven part, means for advancing the commutator brushes adapted to be operated by the driven part of the clutch, means for maintaining a permanent rotary 5 connection between the driving part of the clutch and the rotary part of the lift mechanism, electric means for operating the clutch, means for completing and breaking the electric circuit operating the clutch and means 10 for returning the brushes to the initial position when the circuit is broken.

2. In association with a lift having a rotary part and operated by a polyphase motor having a commutator and commutator 15 brushes the combination of a clutch having a driving and a driven part, means for advancing the commutator brushes adapted to be operated by the driven part of the clutch, a shaft permanently in rotary connection 20 with the rotary part of the lift mechanism and carrying the driving part of the clutch, electric means for operating the clutch, means for completing and breaking the electric circuit operating the clutch and means 25 for returning the brushes to the initial position when the circuit is broken.

3. In association with a lift having a rotary part and operated by a polyphase motor having a commutator and commutator 30 brushes the combination of a clutch having a driving and a driven part, means for advancing the commutator brushes adapted to be operated by the driven part of the clutch, a shaft permanently in rotary 35 connection with the rotary part of the lift mechanism and carrying the driving part of the clutch, a solenoid core, a mechanical connection operatively connecting the solenoid core with the clutch, an electrical circuit 40 cut for energizing the solenoid, means for completing and breaking the electric circuit for the solenoid and means for returning the brushes to the initial position when the circuit is broken.

45 4. In association with a lift having a rotary part and operated by a polyphase motor having a commutator and commutator brushes, the combination of a clutch having a driving and a driven part, means for advancing the commutator brushes adapted to be operated by the driven part of the clutch, a shaft permanently in rotary 50 connection with the rotary part of the lift mechanism and carrying the driving part of the clutch, a solenoid core, a mechanical connection operatively connecting the solenoid core with the clutch, an electric circuit for energizing the solenoid, means for completing and breaking the electric circuit of the 55 60 solenoid and weights operatively connected with the commutator brushes adapted to return the brushes to their initial position on breaking the electric circuit.

5. In association with a lift having a 65 rotary part and operated by a polyphase

motor having a commutator and commutator brushes, the combination of two brush rocker rings carrying the commutator brushes of the motor, a clutch having a driving and a driven part, a rotary member operated by the driven part of the clutch, means operatively connecting the rotary part of the lift mechanism with the driving part of the clutch, a rocker shaft, two levers on the rocker shaft, couplings connecting said levers to the brush rings, a third lever on the rocker shaft, operative connections between the third lever and opposite sides of the rotary member operated by the driven side of the clutch, electric means for operating the clutch, means for completing and breaking the electric circuit operating the clutch and means for returning the brushes to the initial position when the circuit is broken. 70 75 80 85

6. In association with a lift having a rotary part and operated by a polyphase motor having a commutator and commutator brushes, the combination of two brush rocker rings carrying the commutator 90 brushes of the motor, a clutch having a driving and a driven part, a rotary member operated by the driven part of the clutch, means operatively connecting the rotary part of the lift mechanism with the driving part of the clutch, a rocker shaft, two levers on the rocker shaft, couplings connecting said levers to the brush rings, a third lever on the rocker shaft, operative connections between the third lever and opposite sides of the rotary member operated by the driven side of the clutch, an arm on the rocker shaft, a weight pendent from the arm adapted to return the rocker shaft to normal position, electric means for operating the 95 clutch and means for completing and breaking the electric circuit. 100

7. In association with a lift having a rotary part and operated by a polyphase motor having a commutator and commutator 110 brushes, the combination of two brush rocker rings carrying the commutator brushes of the motor, a clutch having a driving and a driven part, a rotary member operated by the driven part of the clutch, means operatively connecting the rotary part of the lift with the driving part of the clutch, a rocker shaft, two levers on the rocker shaft, couplings connecting said levers with the brush rings, a third lever on the rocker 115 120 shaft, operative connections between the third lever and opposite sides of the rotary member operated by the driven part of the clutch, electric means for operating the clutch, means for completing and breaking the electric circuit, means for returning the brushes to the initial position when the circuit is broken and a dash-pot to control the speed of the return movement of the rocker 125 130 rings.

8. In association with a lift having a rotary part and operated by a polyphase motor having a commutator and commutator brushes, the combination of two brush rocker rings carrying the commutator brushes, a clutch having a driving and a driven part, a rotary member operated by the driven part of the clutch, means operatively connecting the rotary part of the lift with the driving part of the clutch, lugs on the brush rocker rings, stops on the frame of the motor with which the lugs engage to limit the movement of the rocker rings, a rocker shaft, lever arms on the rocker shaft,

rods connecting the rocker rings with the 15 lever arms of the rocker shaft, a third lever on the rocker shaft, means operatively connecting the third lever with opposite sides of the rotary member operated by the driven part of the clutch, electric means for operating the clutch, means for completing and breaking the electric circuit, and means for returning the brushes to the initial position when the circuit is broken. 20

In witness whereof I have hereunto set 25 my hand.

PERCY HERBERT STEVENS.
